LIQUEFIED PETROLEUM GAS SYSTEM

Harold L. Norway, Evanston, Ill., assignor to The
Bastian Blessing Co., Chicago, Ill., a corpora-
tion of Illinois

Application January 18, 1941, Serial No. 375,978

25 Claims. (Cl. 62—1)

The present invention relates to a system for storing and dispensing liquefied petroleum gas under pressure including a combination and arrangement of elements for filling and unloading the container or tank in which the liquefied petroleum gas is stored.

The present application is a continuation in part of an application for a Valve, Serial No. 308,684, filed by Harold L. Norway, December 11, 1939, reference to which is hereby made.

After a storage tank has been placed in operation and filled with liquefied petroleum gas, it becomes necessary upon occasion to unload or empty the tank for repair, removal or replacement, and also to drain off heavy ends or replace a winter gas with a summer gas for seasonal operating conditions.

With conventional systems it is difficult, if not impossible, to unload the tank rapidly and with safety. Excess flow check valves interfere with rapid withdrawal in wet gas systems and dry gas systems require complicated mechanisms for the purpose.

It is one of the objects of the present invention to provide an improved system and method for filling and unloading tanks under pressure, and further to provide a system in which an unlicensed withdrawal is hampered to such an extent as to discourage the practice.

A further object of the invention is to provide equipment readily convertible to fill or unload a pressure container at will and to accomplish this preferably through one port where elements must be operated in a predetermined relationship for the unloading of the container.

Another purpose of the invention is to utilize equipment conventionally employed to fill the tank, to also empty the tank as using the same fill hose with a reversible pump upon a service truck.

Another object is to provide a combination of tank and fitting construction characterized by safeguards against unsafe removal of gas and other contingencies experienced in unloading pressure containers.

The present invention also provides an improved means for maintaining house service independently of liquid unloading.

Another object of the invention is to provide an improved system in which stratified heavy ends in the tank are stirred up in the filling operation, and withdrawn first from the tank in the unloading operation. In this connection, one of the objects of the invention is also to provide a withdrawal system which permits the light ends in the tank to maintain a gauge pressure which assists a suction pump in unloading operations.

A further object is to provide a system and combination of elements of the class described

which are easy to fabricate and assemble, and which are rugged in use and simple to operate.

These being among the objects of the invention, other and further objects will become apparent from the drawings, the description relating thereto and the appended claims.

In the drawings:

Fig. 1 is a side elevation of one form of the apparatus mounted in association with the storage tank;

Fig. 2 is a plan view on an enlarged scale of a part of the apparatus shown in Fig. 1;

Fig. 3 is a vertical section taken at line 3—3 of Fig. 2;

Fig. 4 is a vertical section of the apparatus of Fig. 2 taken at line 4—4 of that figure;

Fig. 5 is a longitudinal section through a modified form of the invention in which it is embodied in a single connection, the parts being shown in the closed or inactive position;

Fig. 6 is a view similar to Fig. 5 showing the device of that figure associated with means for withdrawing fluid from the tank; and

Fig. 7 is a section similar to Fig. 5 illustrating another and more compact embodiment of the invention.

By way of illustrating representative conditions relating to the storage and the handling of liquefied petroleum gas, the invention is illustrated in an embodiment where the storage tank is buried in the earth. This refers the invention to another condition which requires unloading, namely, that if the tank were to be raised and exposed to the warmth of sun-light, it would have to be emptied or liquefied petroleum gas such as propane or butane, stored therein.

The system illustrated, preferably has the tank located below the frost line 2 or below the level to which the ground will freeze under the weather conditions prevailing where the tank is installed.

A manhole casing 3 may be secured to the tank or mounted adjacent to it to provide a space for the filling, emptying and dispensing connections and parts. The casing 3 will normally be provided with a cover 4 which may be removably secured in any desired manner, and, ordinarily, some means is provided in the cover or the casing to permit circulation of air into and out of the casing and to allow for relief valve venting

such as a vent 4a. The invention is not limited to any particular tank or tank assembly of course, but may be used with above or below ground installations.

As shown in the first four figures, a standpipe or dome 5 is welded to the tank at 6 to form an integral extension of the tank and at the top thereof, the pipe is preferably threaded to receive a unitary housing member 7. The interior of the standpipe communicates with the interior 60 of the tank and the housing member 7 may be

of almost any desired shape, preferably being provided with a hollow chamber 11 in communication with the tank through the standpipe as shown provided with a round section 3 that is interiorly threaded as at 9 with a tapered thread to engage the threading 10 on the upper end of the standpipe 5 in gas tight relationship. Other appropriate means of securing may be employed.

A hollow branch 12 communicates with the chamber 11 and is provided with an opening 13 about which is formed a valve seat 14. A safety or pressure relief valve 15 is movably mounted adjacent the seat and is provided with a relatively compressible seating portion 16, removably held in position in the valve body in a flanged, threaded retaining member 17.

The safety valve itself is provided with an upwardly extending portion 18 in which is formed a hollow 19. The valve may be generally rounded in cross section or otherwise shaped. As here shown, ducts or passages 20 are formed in its interior to permit passage of fluid past the valve when it is unseated. A spring retaining member 21 is threadingly engaged with the threads 22 formed in the branch 12. This spring retainer is provided with one or more perforations 23, and a spring 24 is seated with one end against the spring retainer, its other end being against the valve 15 and within the cavity or depression 19.

The hollow branch 12 communicates with the main chamber 11 through a passage 25. A second passage 26 communicates with the chamber 11 and with the interior of a second hollow branch or arm 27. As shown, this branch is of use for certain installations, as when it is desirable to have greater pressure relief capacity, in which case the upper wall of the branch 27 will be cut away to provide for the installation of a second or additional pressure relief valve which will be generally like that shown in detail, in Fig. 3 and described above.

It is preferred to fill and empty the tank through the housing member 1 and through a single opening. This is accomplished by forming a hollow boss 28 preferably integral with the housing and providing it with a threaded opening 30 between the interior 29 of the boss and the chamber 11 to receive a pipe 31 which extends to a point close to the bottom of the tank, as shown in Fig. 1, and a liquid connection opening outside of the housing.

The liquid outlet and inlet connection as shown in Fig. 3 is formed in a portion 32 which is preferably integral with the main housing 8. A depression 33 is formed in the member 32, and an annular depression 34 is formed about it. A stem 35 of a valve member 36 is slidably positioned in the depression 33. 36a is a projection formed on the upper surface of the valve 36. A spring 37 is positioned about the stem 35; one end rests within the annular depression 34 and the other bears upon the valve 36 and tends to hold it, when free to do so, upon the seat portion 38 of the annular member 39. This member is removably seated in the threaded portion 40 of the housing section 32. It is provided with one or more perforations 41 through which fluid may pass in or out. It is also provided with a cylindrical, outwardly directed section 42 within which a stem 43 of a second valve member 44 is positioned.

A spring 45 is positioned about the cylindrical portion 42 and about the valve stem 43. It bears

at one end upon portions of the member 38 and at the other upon the bottom of the valve 44, and tends to hold it closed, when free to do so. A seating portion of compressible material 46 is preferably removably mounted on the upper or outer face of the valve 44 and held in place by a washer 47 and a screw 48. A connection and seating member 49 is removably engaged in the threaded portion of the housing section 32. It is provided on its inner or lower end with a seat portion 50 against which the member 46 of the valve 44 is seated when the valve is closed. Adjacent its upper end, the member 49 is interiorly threaded as at 51 to receive a closure plug 52. The member 49 is also exteriorly threaded as at 53 to receive a filling hose or adapter connection. The closure plug is provided with an overhanging, downwardly disposed peripheral flange 54 which overlies and covers, to some degree at least, the threads 53 when the plug is in the closed position. A gasket 55 may be positioned within a groove or undercut portion 56 formed in the open, upper end of the member 49, and a shoulder 57 of the closure plug seats against, and to some degree compresses this gasket when the plug is in the closed position.

Formed generally within the branch or arm 27 is a passage 60 which communicates at its inner end with the interior of the housing 7, and particularly with the chamber 11 through an enlarged branch passage 75 having a threaded opening 61 at the lower end thereof and a valve seat 80 at the top. Adjacent its outer end, the passage 60 is provided with a valve seat 62 within which a shutoff valve 63 is normally positioned. This valve has a threaded portion 64 seated in corresponding threading 65. Packing 66 surrounds the shaft-like portion 67 which is formed integrally with or attached to the valve 63. A packing gland 68 is mounted to compress the packing 66.

At its outer end, the shaft 67 is squared or given any other angular shape 69 by means of which it may be engaged by a tool for rotation to move it into or out of seating position. A cover or cap 70 is received upon the threaded portion 71, and may have laterally extending wing portions 72 by means of which it may be rotated, and it may have an angular cavity 73 used to rotate the stem 67. An outlet passage 74 branches downwardly from the passage 60 beyond the seat 62 and is threaded as at 82 to receive the nipple portion of a swivel connection and nut 83 by which a pressure regulator 87 is secured in place. The pressure regulator 87 may be of any desired type or capacity. From the regulator 87, a pipe 88 leads through a connection 89 to a second pipe 90 which leads to the point of use of the fluid which passes through the system. 91 is a pressure-vent tube which, if desired, may be attached to the regulator 87.

Within the enlargement 75 is positioned an excess flow check valve member 77, which as shown is provided with drilled passages 78 therethrough to permit a predetermined amount of vapor or liquid to flow therethrough with a spring 79 holding the valve open against the flow of fluid within the limits determined. A retainer 81 holds the valve and spring in position. When the flow is excessive the valve closes against the seat 80. 76 is a small by-pass opening through the excess flow check valve member 77 which permits equalization of pressure so that the excess flow check valve can open once it has closed.

With this arrangement it is possible to service the valve 63 and packing 68 whenever necessary and rapid withdrawal of liquid is prevented in large quantities if a person seeking to unload the tank removed the valve 63 or the regulator 81 to make connection with an unloading hose at either of these points. The top or upper surface of the housing 7 is provided with an opening 58 to receive a slip tube gauge 59 or the like therein to gauge the level of liquid in the tank.

The valves 36 and 44 preferably have the same port area, allowance being made for the stud 36a on the top of the valve 36 which is contacted by the stem 43 of the valve 44 when the valve 44 is positively displaced downwardly. With this particular arrangement the valves are capable of opening independently of each other when forced open by incoming fluid pressure and dependently, one upon the other, when the top valve 44 is depressed by a positive force which otherwise is not effective separately for both valves.

The particular arrangement shown is of an advantage upon filling operations where the pressure of the incoming fluid may not be very great in some instances both valves being preferably identical where the port areas are the same. However, when it is desirable to unload the tank, mechanical means can be used which is conveniently strong enough to overcome the additive pressure of both springs with little difficulty.

A modification of this valve arrangement and operation is shown in Figs. 5 and 6 which comprises a hollow housing 82, preferably threaded exteriorly as at 83 to be received into a corresponding threaded opening in a container. The housing is provided with an internal spider 94 which has one or more perforations 95 formed in it. On its lower or inner face, the spider has a valve seat 96 against which a valve 97 may be seated. The valve is provided with a stem 98 mounted for sliding movement in a central portion 99 of a spider 100 which is provided with one or more perforations 101. This spider is formed in a separate or additional section 102 which is threadedly engaged with the main housing section 82. It may be interiorly threaded as at 103 to receive a pipe connection if desired.

A spring 104 is positioned to bear at one end against the valve 97 and at the other end against the spider 99 or the portion 100 of that spider. Upon its upper face, the valve 97 has a raised projection 105 which is adapted to contact the valve stem 106 of the valve 107. This stem is mounted to slide in the spider 94. A spring 108 bears at one end against the spider 94 and at the opposite end against the valve 107. This valve may carry on its seating face a compressible member 107a which is removably held in place by a washer 109 and a screw 110. A connecting and seating member 111 is in threaded engagement with the housing 82, and it has formed on its inner face a valve seat 112 against which the valve portion 107a may be seated.

At its upper end the member 111 is interiorly threaded as at 113. It is also exteriorly threaded as at 114. A closing plug 115 may be removably seated in the threads 113. This plug is provided with a downwardly depending peripheral flange 116 which, when the plug is in the closing position, overlies some, at least, of the threads 114. A gasket 117 may be mounted in a groove 118 within the housing section 111; and a shoulder 119 on the closing plug 115 bears against and to some degree compresses this gasket when the plug is seated.

As shown in Fig. 6, the seating plug 115 has been removed and in its stead positive displacement means have been provided for withdrawing liquid from the tank or container to which the connector assembly is secured. As shown, 5 a connector 120 has been inserted in the place of the closing plug 115. This connector is exteriorly shouldered as at 121, and a connecting collar 122, having a flange 123, surrounds the member 120 and engages the threads 114 and, 10 thus, the member 122 is held in position upon the threads 114 of the member 111. The gasket 117 is compressed by the shoulder 124 of the member 120. Positioned within the member 120 is a valve operating part 125. As shown the part 125 is hollow. At its lower end it is provided with a contacting point 126 and it has one or 15 more passages or openings 127 formed in its lower end. It is preferably shouldered as at 128 at its upper end. Secured to the upper end of the member 120 is an internally threaded tubular member 129 which is also externally threaded tubular member 129 which is also externally threaded as at 130 to receive a hose coupling. 20 A gasket 131 is received in a groove 132 formed in the member 129. A hose connection 133 may be inserted within and connected to the member 129 and held in place therein by a coupling nut 134 which is interiorly threaded as at 135 and 25 provided with an inwardly directed flange 136 which engages a shoulder 137.

By this means the hose connection is held in place and the valve operating member 125 is depressed to open the valve as shown in Fig. 6. 30 A hose, which is not here shown, may be secured to the upper or free end of the hose connector 133 in any desired manner.

Referring to Fig. 7 another modification is shown which is very compact in form, one valve being receivable within the confines of the other. 40 In this particular embodiment, the housing 111 is threaded into the top of a fitting 150 which fitting has a valve seat 151 proximate to and larger than the valve seat 112 upon the lower 45 end of the housing 111. A spider 152 is threaded into the bottom of the fitting 150 to support the stem 153 of the lower valve 154 for reciprocation in an opening 155 through a central boss 156 upon the spider. The spring 156a urges the lower valve upwardly into contact with the seat 151. The lower valve 154 is hollowed out to receive the upper valve 157 therein which carries a resilient seat 107a into contact with the seat 112. The upper valve is small enough to clear 50 the seat 151 for removal and repair whenever the housing 111 is removed for that purpose.

The stem 158 of the upper valve 157 is reciprocably received in a closed-bottom guide-opening 160 in the stem 153 and is urged into contact 55 with the seat 112 by a spring 161 resting upon the shoulder 162 at the bottom of an enlargement 163 made to receive the spring 161 in the body of the lower valve.

In this particular embodiment the valve areas 60 are of different sizes but operate substantially in the same way as already described.

As shown in Figs. 3 and 4 particularly, the threaded opening 61 may be left open, for some purposes, as where dry gas withdrawal is desired. On the other hand in some systems it 65 is preferable to position a small pipe shown in broken lines 164 in the opening 61 and to have it extend downward into the liquid within the tank. The opening may, thus, be used exactly 70 as shown or with a tube installed.

Ordinarily, a pressure gauge is desirable. One such is shown in Fig. 2 as at 188. It has a dial 189 and a needle or pointer 140. It is connected by means of a tube 141 to the housing branch 12 in the wall of which an opening 142, as shown in Fig. 3, is formed in register with the pipe 141.

Although several forms of the invention are shown and described, it will be understood by those skilled in the art that many changes in the form, relative dimensions, shape and arrangement of parts might be made without departing from the spirit of the invention, the scope of which is commensurate with the appended claims.

The use and operation of this device are as follows:

The closure plug 52 is removed. A hose connection, generally similar to that shown in Fig. 6, is connected. The other end of the hose is connected to a source of liquid; for example, to a tank, truck tank, or tank car. Suitable valves are opened and the liquid flows through the hose and comes against the uppermost valve 44, opening it by compressing the spring 45. The stem of the valve 44 contacts the member 36a of the valve 36 and opens this valve, also, against the resistance of the spring 37, and the liquid flowing past both valves enters the tube 31 and flows to the bottom of the tank. Sometimes the weight of the liquid alone or the pressure of a warm service tank is sufficient to open the valve and to cause the liquid to flow into the tank. Sometimes it is not sufficient, and a pump on the tank truck or elsewhere is used to force the liquid into the tank. Opening of the first valve is followed by the opening of the second valve at times independently of each other without need for additional pressure. When a sufficient quantity of liquid has been forced into the tank, further flow is stopped, the hose connection is removed, the valves will have been closed, either by vapor pressure within the tank or in response to their respective springs or in response to both of these effects. If the hose has been removed, the closure plug is re-inserted. As a precautionary measure, the fitting 49 is undercut as at X; and should some unexpected breaking occur, the fitting will break at the point X above the valves and they will then automatically close to prevent discharge of liquid or any fluid from the tank.

With the tank now suitably filled with gas, some vapor will be present. Ordinarily, this vapor will pass up the standpipe 5 and outward through the opening 61 and the passage 60. Usually, when the system is first installed, the valve 63 will be seated. After the tank is full and when the system is to be put into use, the valve will be opened, being backed away from the seat 62 and vapor then passes from the passage 60 to the passage 74, moving past the check valve 77, outward through the opening 60 and through the nipple of the swivel connection 83. If a pressure regulator is installed, the fluid moves to it from the nipple of the swivel connection 83 and from the regulator, it moves through the pipes 88 and 90 to the point of use. The invention is not limited to the use of a regulator, and in case one is used, the invention is not limited to any particular type. No regulator may be present, or several regulators may be used if desired.

For some purposes, it is desirable to permit liquid or a mixture of vapor and liquid to leave the system for use. Where that is done, a pipe

is inserted in the opening 61 and extends downward into the liquid.

Vapor pressure within the tank will force this liquid upward through the pipe and into the passage 60, and from there it follows the path above described for the vapor alone. Where liquid is, thus, discharged from the tank for using, some means is provided for accomplishing its vaporization before it reaches the point of use.

110 A number of such means are available and the invention is not limited to any particular one.

Should the flow of fluid through the passages 61, 74 be too rapid or otherwise unsatisfactory, the check valve 78 will be moved upward against 15 the spring 79 and will be seated upon the upper surface of the member 80, thus stopping the flow.

Occasionally it is necessary to empty a tank by withdrawing the liquid from it. Where that is necessary, the closure plug 52 is removed, as 20 it would have been for filling, and a member such as the member 125 of Fig. 6 is inserted with the connections there shown, a hose having been previously connected to the member 133. At its other end, the hose is connected to a suitable 25 receptacle into which the liquid is to be deposited.

When the member 125 is put into position and the hose connection is tightened upon it, it contacts the screw 48 on the valve 44 and moves that valve open. The stem 43 contacts the projection 36a of the valve 36 and opens it. The two valves are, thus, held open while the member 125 is in place, and liquid may now be pumped out of the tank through the pipe 31 until the tank is wholly or substantially empty. Then the 35 member 125 and the hose connection are removed and the empty tank may be repaired or removed or otherwise treated. It will be noticed that the connector 129 has a relatively narrow section at the point Y; and should side pressure occur on the connections, it will break at that point rather than at the point X on the member 49. When that occurs, there is nothing to hold the member 125 down in the valve opening 40 position, and the valves will thereupon close either in response to their springs or to pressure 45 from within the tank or in response to both.

Installations of the type shown in the first four figures ordinarily require a pressure release or safety valve mechanism. Figs. 3 and 4 show such a mechanism. Excess pressure will be effective on the valve 15 and will cause it to yield outwardly against the resistance of the spring 24 and, thus, pressure is released from the system. As above mentioned, more than 50 one pressure release valve may be installed. This will be done where a greater pressure release capacity is required than could be conveniently furnished by means of a single valve.

Ordinarily, some sort of liquid level gauge is 55 provided. The opening 58 and the pipe 59 merely indicate diagrammatically a suitable location for such a gauge, which may be of any desired type—mechanical, electrical, slip-tube or other type.

60 What is claimed is:

1. In combination with a tank, a hollow housing formed of a unitary member and connected to said tank in communication with its interior, parts of said unitary member defining an inlet 65 and a discharge passage for moving fluid into and withdrawing it from said tank, a pipe secured in communication with said passage and extending into said tank, a plurality of valves 70 in said housing opening in the direction of the flow of fluid introduced into the tank under

pressure, means normally holding them closed against said flow, parts on the valves adapted to contact each other whereby opening movement of the outermost valve to a predetermined degree accomplishes an opening of an adjacent valve.

2. In combination with a tank, a hollow housing formed of a unitary member, means for securing the unitary member in communication with its interior, parts of said unitary member defining an inlet and a discharge passage for moving fluid into and withdrawing it from said tank, a pipe secured in communication with said passage and extending into said tank, a plurality of valves in said housing disposed in said passage for controlling the flow of fluid therethrough, means normally holding them closed, parts on the valves adapted to contact each other whereby opening movement of the outermost valve accomplishes opening of any adjacent valve, and a removable connector assembly adapted to be secured to said housing and including a hollow valve-operating member which moves said outermost valve to the open position.

3. In combination with a tank, a hollow housing formed of a unitary member secured to the tank in communication with its interior, parts of said unitary member defining an inlet and a discharge passage for moving fluid into and withdrawing it from said tank, a pipe secured in communication with said passage and extending into said tank to a point adjacent the bottom of the tank, a plurality of valves in said housing for controlling the flow of fluid through the passage, means normally holding them closed, parts on the valves adapted to contact each other whereby opening movement of the outermost valve accomplishes opening of an adjacent valve, and a removable connector assembly adapted to be secured to said housing and including a hollow valve-operating member which moves said outermost valve to the open position.

4. In combination with a tank buried in the ground, a standpipe extending upwardly to a point accessible above the ground, a hollow housing formed of a unitary member and secured to the upper end of said standpipe and in communication with its interior, parts of said unitary member defining an inlet and a discharge passage for moving fluid into and withdrawing it from said tank, a pipe secured in communication with said passage and extending through said standpipe into said tank to a point adjacent to the bottom of the tank, a plurality of valves in said housing disposed in said passage to control the flow of fluid through the passage, means normally holding them closed, parts on the valves adapted to contact each other whereby opening movement of the outermost valve to a predetermined degree accomplishes opening of an adjacent valve.

5. In combination with a buried tank, a standpipe extending upwardly from the tank, a hollow housing formed of a unitary member and secured to the top of said standpipe in communication with its interior, parts of said unitary member defining an inlet and a discharge passage for moving fluid into and withdrawing it from said tank, a pipe secured in communication with said passage and extending through said standpipe into said tank to a point adjacent the bottom of the tank, a plurality of valves in said housing disposed in said passage, means normally holding them closed, parts on the valves

adapted to contact each other whereby opening movement of the outermost valve accomplishes opening of an adjacent valve, and a removable connector assembly adapted to be secured to said housing and including a hollow valve-operating member which moves said outermost valve to the open position.

6. In combination with a tank, a valve housing formed of a unitary member secured in sealed communication with the interior of said tank, there being within said housing a plurality of valve seats and valve-supporting means connected by a passage, and a plurality of valves movably mounted therein, means for each valve tending to seat it, when free to do so, said valves provided with portions which, when the one valve is opened by positive displacement, will contact each other and will transmit opening movement from the one valve to the other valve to open the latter, and a connector assembly adapted to be removably secured to said valve housing, said connector assembly including a hollow valve opening member adapted, when seated, to open the outermost valve to such degree as to cause opening of an adjacent valve.

7. In combination with a tank for storing liquefied gas having a standpipe or the like, an integral hollow unit secured to the standpipe in communication with the interior of the tank, a passageway through a wall of the unit defining a conduit through which fluid may be moved, means for conducting fluid from the tank to the passageway, a safety check valve in the passageway closing with the flow of fluid from the tank, a self closing check valve in the passageway opening with the flow of fluid into the tank, means interconnecting the valves including a lost motion device permitting said valves to operate independently of each other at times when the tank is receiving liquefied gas and one independently upon the other when the tank is being emptied.

8. In combination with a tank having a standpipe or the like, a unitary housing on the standpipe having a cavity in communication with the interior of the tank, said housing having a service outlet and a filling passageway independent of one another, an excess flow check valve in the outlet, a safety check valve in the passageway closing with the flow of fluid from the tank, a self closing valve in the passageway opening with the flow of fluid into the tank, and removable connector device for withdrawing fluid from the tank so constructed and arranged as to force said self closing valve and safety check valve open by simultaneous positive displacement of the valves cooperatively whenever the device is attached to the housing.

9. In combination with a tank, a unitary housing mounted on the tank and having a cavity in sealed communication with the interior of the tank, said housing having a service outlet and a filling passageway independent of one another, an excess flow check valve in the outlet to control ejection from the tank under service conditions, tandem valves opening at times independently of each other under fluid pressure and cooperatively with each other when positively displaced, a removable connector device for withdrawing fluid from the tank so constructed and arranged as to positively displace said valves cooperatively whenever the device is attached to the housing.

10. In combination with a tank for storing

liquefied petroleum gas, a unitary housing having a cavity therein, means for securing the housing to the tank including an element providing a conduit communicating with the cavity at one end and opening near the bottom of the tank at the other end, a filling passageway through a wall of the housing and opening into the cavity, a safety check valve in the cavity closing with the flow of liquid from the tank, a second valve in the cavity controlling the flow of fluid out of the tank, manual means for positively displacing the second valve, and means for opening the first valve by the second valve when the second valve is opened beyond the predetermined minimum.

11. In a liquefied petroleum gas dispensing system, the combination of a tank for storing gas under pressure, a fitting connected to the tank and having a space in the body portion thereof in communication with the tank, a passage through the wall of the fitting, a conduit extending to the bottom of the tank connected to one end of the passage, a plurality of safety check valves in tandem in said passageway, means for connecting a conduit to the fitting at the other end of the passage, and a service conduit communicating with the interior of the tank and having a manual control valve therein and an excess flow check valve therein.

12. In a liquefied petroleum gas dispensing system, the combination of a tank for storing gas under pressure, a fitting connected to the tank and having a space in the body portion thereof in communication with the tank, a passage through the wall of the fitting, a conduit extending to the bottom of the tank connected to one end of the passage, a safety check valve in said passageway closing against one seat, a second safety check valve carried by the first valve and closing against a second seat, means for connecting a conduit to the fitting at the other end of the passage, a service conduit communicating with the interior of the tank and an excess flow check valve in said conduit.

13. In a liquefied petroleum gas dispensing system, the combination of a tank for storing gas under pressure, a fitting connected to the tank and having a space in the body portion thereof in communication with the tank, a passage through the wall of the fitting, a conduit extending to the bottom of the tank connected to one end of the passage, a plurality of safety check valves in said passage normally closing in the direction of flow of gas from the tank, means for connecting a conduit to the fitting at the other end of the passage, and an angular service conduit communicating with the interior of the tank, a manual control valve therein upon one side of the angle, and an excess flow check valve therein upon the other side of the angle.

14. In a liquefied petroleum gas dispensing system, the combination of a tank for storing gas under pressure, a fitting connected to the tank and having a space in the body portion thereof in communication with the tank, a passage through the wall of the fitting, a conduit extending to the bottom of the tank connected to one end of the passage and extending through said space, a plurality of check valves in said passage closing in the direction of flow of fluid from the tank, means for connecting a conduit to the fitting at the other end of the passage, a service conduit communicating with the interior of the tank through said space, a manual control valve in said conduit and an excess flow

check valve in said conduit between the manual control valve and said space.

15. In a liquefied petroleum gas dispensing system, the combination of a tank for storing gas under pressure, a fitting connected to the tank and having a space in the body portion thereof in communication with the tank, a passage through the wall of the fitting, a conduit extending to one end of the passage and extending through said space, a plurality of check valves in tandem in said passage closing in the direction of flow of fluid from the tank, means for connecting a conduit to the fitting at the other end of the passage, a service conduit communicating with the interior of the tank and terminating in a threaded opening adapted to receive a liquid ejection tube, a manual control valve and an excess flow check valve in said conduit.

20. 16. In a liquefied petroleum gas dispensing system, the combination of a tank for storing gas under pressure, a fitting connected to the tank and having a space in the body portion thereof in communication with the tank, a plurality of passages through the wall of the fitting, a conduit extending to the bottom of the tank connected to the inner end of one of the passages, a plurality of check valves in said one passage closing in the direction of flow of fluid from the tank, means for connecting a conduit to the fitting at the outer end of one passage, an excess flow check valve proximate said space and a manual control valve in another of said passages, a safety relief valve in another passage, and a manually opened check valve in another of said passages for venting the tank from said space.

25. 17. In combination with a tank; a hollow valve housing formed of a unitary member secured in sealed communication with the interior of said tank, there being disposed within said hollow housing a valve seat and valve supporting means; a removable hollow section secured to the housing, said removable section including a valve supporting member; a second removable section adapted to be joined to the opposite end of said hollow valve housing and having a valve seat formed therein; said valve housing, valve supports and hollow section comprising a passageway placing the interior of the tank in communication with the outside; a valve in said valve housing; means tending normally to move said valve to its closed position when free to do so; a valve in said first-mentioned removable section; and yielding means tending normally to close the last said valve, when free to do so; the two valves having parts adapted, when the outermost valve is opened to a predetermined degree, to cause opening of the adjacent valve in response to opening of the outer valve.

30. 18. In combination with a tank; a valve housing formed of a unitary member and secured in sealed communication with the interior of said tank, there being within said housing a passage, a valve seat and valve supporting means; a removable hollow section secured to the valve housing, said removable section including a valve supporting member; a second removable section adapted to be joined to the opposite end of said valve housing and having a valve seat formed therein; a valve in said valve housing; means tending normally to move said valve to its closed position, when free to do so; a valve in said first-mentioned removable section; and yielding means tending normally to close the last said valve.

when free to do so; the outer of said valves being opened by pressure and positive displacement and the inner of said valves checking the outflow of said fluid from the tank, the two valves having parts adapted, when the outermost valve is opened to a predetermined degree by positive displacement, to contact each other and to cause opening of the adjacent valve in response to opening of the outer valve.

19. In combination with a tank for storing liquefied gas, a unitary fitting secured in sealed communication with the interior of said tank and having a passageway therethrough defining a conduit through which fluid may be moved, means for conducting fluid from the tank to the passageway, a check valve in the passageway closing with the flow of fluid from the tank, a self closing check valve in the passageway opening with the flow of fluid into the tank, means interconnecting the valves including a lost motion device providing independent movement between said valves at times when the tank is being filled and dependent movement between the valves when the tank is being emptied, in which dependent movement the movement of one valve to its open position operates to hold the other valve open.

20. In combination with a tank for storing liquefied petroleum gas having a boiling point below the freezing point of water, a unitary housing secured in sealed relationship with the tank and having a cavity therein in communication with the interior of the tank, said housing having a filling passageway through which fluid may move, a check valve in the passageway closing in the direction of flow of fluid from the tank, a self closing check valve in the passageway opening with the flow of fluid into the tank, said valves opening independently of each other at times when fluid is forced into the tank, conduit means connecting the cavity with the bottom of the tank, and means for opening the valves in a predetermined relationship for withdrawal of liquid from the tank through said conduit means.

21. In a hollow valve housing, a plurality of valve seats and valve-supporting means, and a plurality of valves movably mounted therein, means for each valve tending to seat it, when free to do so, said valves provided with portions which, when the one valve is opened, will transmit opening movement from the one valve to the other valve to open the latter, a connector assembly for a filler conduit adapted to be removably secured to said valve housing, said connector assembly including a removable hollow valve opening member adapted, when seated, to open the outermost valve by mechanical displacement and thereby to cause opening of an adjacent valve, and a fitting supporting said filler conduit and detachably receiving said valve opening member.

22. In a coupling for servicing a storage tank, a valve housing having a passage therethrough, a plurality of valve seats and valve supporting means in the passage, and a plurality of valves movably mounted therein, means for each valve tending to seat it, when free to do so, said valves positioned adjacent each other, and provided with portions which, when the one valve is opened, will transmit opening movement from the one valve to the other valve to open the latter, and a connector assembly adapted to be removably secured to said valve housing, said con-

necter assembly including a fitting for supporting a flexible conduit and a hollow valve opening member detachably received upon the fitting and adapted, when seated, to open the outermost valve and thereby to cause opening of an adjacent valve.

23. In a hollow valve housing, a plurality of valve seats and valve-supporting means, and a plurality of valves movably mounted therein, means for each valve tending to seat it, when free to do so, said valves provided with portions which, when the one valve is opened, will contact each other and will transmit opening movement from the one valve to the other valve to open the latter, and a connector assembly adapted to be removably secured to said valve housing, said connector assembly including a hose connecting element with a coupling nut thereon, a coupling member receiving said nut in threaded relation, a second coupling nut carried by the coupling member, and a hollow valve opening member extending beyond the second coupling nut secured in place by the first coupling nut and coupling member, said hollow valve opening member adapted under force exerted by the second coupling nut to open the outermost valve and thereby to cause opening of an adjacent valve.

24. Means for filling and rapidly emptying a storage tank which has been placed in operation comprising a portable connector nipple, a housing member adapted to be secured to the tank and having a tube extending to the bottom of the tank, said housing being provided with independent valves and valve seats adapted to be held open conjointly when one of the valves is forced open by insertion of the connector nipple whereby the contents of the tank are forced out by pressure present in the tank, said one of the valves being removable from outside the tank while the tube is in the tank, resilient means disposed inwardly of the respective valves for holding the valves closed against their respective seats, said resilient means being of such strength that when fluid is injected into the tank to fill it, the resistance of the resilient means is overcome by the pressure of the filling fluid.

25. In a device of the class described for filling and emptying an underground tank having liquefied petroleum gas present therein in both its liquid and vapor phases, the combination of a housing member secured to the tank and adapted to be accessible from above the ground, conduit means extending through the housing member and including a pipe which opens at its lower end at a point close to the bottom of the tank, independent valves and valve seats mounted in said conduit means and so constructed and arranged as to be opened conjointly when the outer valve is forced inwardly and open by the insertion of a nipple into the outer end of said conduit means, whereby the contents of the tank in the liquid phase thereof are forced out by the pressure in the tank of the contents present in the vapor phase, means located inwardly of the valves for normally holding the valves closed against their respective seats including resilient elements, the last said means being of such strength as to yield to permit the valves to open under the pressure of inflowing filling fluid when the filling fluid is forced into the tank, and said outer valve being removable from outside the tank for repair and replacement.

HAROLD L. NORWAY.
